UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

COOLING UNIT CONSTRUCTION

Application filed June 10, 1930. Serial No. 460,238.

This invention relates to cooling unit construction, and particularly to efficient and ornamental means for preventing the formation of frost at the front or operating 5 face of the unit.

This application is a continuation in part of my prior application No. 396,190, filed September 30, 1929. In such prior application I disclosed the use of a complete rubber apron for the front of a cooling unit in addition to individual closure members 10 formed of rubber for contacting with the front of the portion of the cooling unit for isolating individual sharp freezing chambers. 15

It is the object of the present invention to provide a rubber front for a lowside or cooling unit similar in a way to the rubber apron disclosed in said above copending application, but preferably of sponge rubber or similar material so as to fill in the space which is usually provided between the front 20 of a cooling unit and the ornamental front frame therefor. In this case sponge rubber or similar material provides all the advantages of the air space heretofore used and in addition efficiently protects the complete front of the cooling unit to permit the insertion or withdrawal of the sharp freezing 25 containers at any time.

Some of the main features of this novel sponge rubber front included the utilization of the air cells so that the front provides a relatively good insulator as well as providing a material to which ice does not readily 30 adhere. Use is made of the relative thickness of the sponge rubber whereby to provide neat and well fitting doors for the sharp freezing chambers and use is also made of the surface openings in the sponge rubber 35 for efficiently wiping off one or more walls of the sharp freezing containers as they are inserted into the respective chambers in the cooling unit.

40 In the drawing:

Fig. 1 is a perspective view of a typical embodiment of the present invention when used in connection with a cooling unit of a domestic refrigerator.

45 Fig. 2 is a fragmentary sectional view of

a cooling unit such as illustrated in Fig. 1 and illustrating the manner of positioning the sponge rubber front between the ornamental plate and the front of the cooling unit as well as the manner of providing means for permitting the insertion and removal of a sharp freezing container.

Fig. 3 illustrates a modified form of front construction wherein reinforcing means are embedded in the rubber to add rigidity as well as resiliency.

Fig. 4 is an enlarged fragmentary view illustrating the manner of clamping the front member between the plate and the cooling unit.

Fig. 5 is a perspective view, partly in section, of a modified form of cooling unit and front construction.

Fig. 6 is a fragmentary longitudinal sectional view of a corner of the unit shown in Fig. 5 showing in detail the manner of clamping the rubber front around its edges.

Regardless of the form of cooling unit, it is substantially universal practice to provide a separate ornamental metal plate which presents a neat false front for the cooling unit and thus completely conceals the same except for openings which register for the sharp freezing chambers of the cooling unit. Such front has usually been spaced from the cooling unit so as to provide an insulating air space designed to prevent or retard frosting up of the ornamental plate. However, unless the operator was very diligent in watching the defrosting operations, it is well known that the cooling unit built up a very thick layer of frost or ice on all sides. One of the uses of the present invention resides in the replacement of this ornamental plate.

A standard cooling block is shown as at 1 in Fig. 2, provided with suitable sharp freezing chambers 2 and sharp freezing containers 3. A standard ornamental frame for the front of the cooling unit is indicated as at 4 and is provided with suitable apertures 5 for registering with the sharp freezing chambers 2.

In the space between the frame 4 and cooling unit 1 I have provided what might be

termed a rubber filler member or front member 6. This member 6 is preferably formed of sponge rubber and of a thickness greater than the distance of the frame 4 of the front 5 of the cooling unit 1. The frame 4 is usually screwed into place on the front of the cooling unit and it will be obvious that the rubber filler or front member 6 can be readily positioned at the front of the cooling unit 10 and the frame member then positioned thereon and screwed home so as to compress a portion of the sponge rubber, as best indicated in Figs. 2 and 4. This space between the frame member and the front of the 15 cooling unit is thus completely filled up with a very efficient insulating material whereby the ornamental frame member, as well as the entire front of the cooling unit is effectively prevented from frosting up. 20 Over long periods of operation I have found that the cooling unit will build up many inches of ice around the sides thereof while the front will remain completely free so that access is had to the sharp freezing compartments at all times. 25

The members 6 may be formed in one single piece or in a series of separate blocks each held in place by a portion of the front frame member 4, as is best illustrated in 30 Fig. 2. Regardless of whether the front member is formed integrally or in separate blocks I prefer to so fabricate the same as to provide door members 7 adapted to register with the sharp freezing chambers of 35 the cooling unit whereby the sharp freezing containers may be readily removed or inserted in place by merely opening the door member or members.

The lower edge 8 of each opening formed 40 by the door members is preferably positioned slightly above the bottom of each sharp freezing container so that when the sharp freezing container is inserted into position as best illustrated in Fig. 2, the bottom of 45 said container will be scraped clean and dry by the sponge rubber edge so as to materially reduce the tendency of the sharp freezing container to stick to the supporting shelf. The wide surface 8 formed by 50 this sponge rubber presents a very effective scraping surface. In addition the thickness of the sponge rubber front makes it possible to obtain a very easy and still a relatively tight fit between the door and its 55 opening.

In the modification shown in Figs. 5 and 6 I prefer to use a molded cooling unit such as stone or the like, and in forming such cooling unit I prefer to use the rubber front 60 as one wall of the complete unit. In forming such a unit I may provide a sheet metal container 9 which may be drawn or stamped in the usual manner so as to be completely enclosed except for the top or front. A 65 plastic stone lining 10 may then be poured

in the usual manner so as to form a stone cooling unit with suitable sharp freezing chambers. Five sides of the sheet metal member 9 will thus completely enclose the stone walls and protect the same from moisture and the like. It will also be understood that suitable refrigerating members are embedded in or positioned in heat conducting relation with the stone wall, as disclosed in my Patent No. 1,671,762. 75

After the stone is poured and sets in place, as illustrated in Figs. 5 and 6, then the sponge rubber mat or front 11 may be inserted in place and the peripheral flange 12 of the container 9 turned over to compress and secure the rubber front in position as best illustrated in Fig. 6. Such rubber front therefore effectively closes up the open end of the stone cooling unit as well as insulating the front of said cooling unit to prevent the formation of frost or ice thereon. The interior of the sharp freezing chambers of the stone cooling unit may be coated with enamel or otherwise covered in any suitable manner. When said rubber front is used as a single integral article, as best shown in Fig. 5, and is held in place at its edges, it presents a very neat appearance and may be given any suitable tint corresponding to the color scheme of the entire unit. 90

What I claim is:

1. In a cooling unit of the type having a fixedly positioned front frame spaced therefrom, the combination of a cover for the cooling unit filling the space between said front frame and cooling unit and held in place by the front frame and having the properties of a relatively good insulator and material to which ice does not readily adhere. 100

2. In a refrigerating cabinet of the type having a freezing compartment, a cooling unit therein, a door for the compartment, sharp freezing chambers, and a fixedly positioned front member between the door and cooling unit and spaced from the cooling unit, the combination of a cover for the cooling unit of compressible insulating material held in position between a surface of said cooling unit and said front member, said cover being provided with door members registering with the sharp freezing chambers. 110

3. A sharp freezing unit comprising a main body having one or more sharp freezing chambers and a sponge rubber cover member secured to the front of said unit for normally sealing the same from the surrounding atmosphere and having one or more door members registering with said sharp freezing chamber or chambers. 125

4. A cooling unit comprising a sharp freezing unit, a front frame therefor and a sponge rubber cover member clamped between the front of said sharp freezing unit 130

and said frame, said sharp freezing unit being provided with one or more sharp freezing chambers and said cover being provided with one or more openings registering with 5 said chamber or chambers.

5. A sharp freezing unit comprising a main body having one or more sharp freezing chambers and a cover member of insulating material for the front thereof having 10 openings registering with said chamber or chambers, the lower surface of the opening or openings in said cover member being positioned adjacent the bottom of said chamber or chambers presenting a wiping 15 surface for the bottom surface of the sharp freezing containers whereby said containers will be wiped off when the same are inserted into position in the sharp freezing chamber or chambers.

20 6. A sharp freezing unit comprising a main body having one or more sharp freezing chambers and a sponge rubber cover member for the front thereof having openings registering with said chamber or chambers, the lower surface of the opening or 25 openings in said cover member being positioned adjacent the bottom of said chamber or chambers whereby the bottom surface of the sharp freezing containers will 30 be wiped off when the same are inserted into position in the sharp freezing chamber or chambers.

35 7. A cover member for the front of sharp freezing units formed of relatively thick sponge rubber, a portion of said cover member being cut away to form a door or doors, the relatively wide cut away portions of the door or doors and the corresponding apertures presenting relatively wide surfaces 40 for sealing the doors.

45 8. A sharp freezing unit having one or more sharp freezing chambers and a ledge adjacent the front lower wall of each chamber presenting a wiping surface for the bottom of the sharp freezing container or containers.

50 9. A sharp freezing unit having interior walls formed of stone and exterior enclosing walls formed partly of metal and partly of rubber.

55 10. A sharp freezing unit having interior walls formed of stone and exterior enclosing walls formed partly of metal and partly of rubber, a rubber enclosing wall being positioned at the front of the unit and provided with means for permitting access to the sharp freezing chamber or chambers of the unit.

60 11. A sharp freezing unit comprising an outer container formed of five walls and interior walls formed of a plastically applied material allowed to harden, said outer container forming a mold for said plastically applied material, one or more sharp 65 freezing chambers within said unit and a

rubber front held in position against the surfaces of the front of said plastically applied material.

12. A sharp freezing unit formed of stone and having one or more sharp freezing 70 chambers, metal walls enclosing at least two sides of said stone unit and a rubber front for said stone unit held in place by said metal side walls.

13. In a refrigerating cabinet of the type 75 having a freezing compartment, a cooling unit therein, a door for the compartment, sharp freezing chambers, and a fixedly positioned front member between the door and cooling unit and spaced from the door, the combination of a cover for the cooling 80 unit of compressible insulating material held in position between a surface of said cooling unit and said front member, said cover being provided with door members registering with the sharp freezing chambers and being imperforate except for the openings 85 formed by the door members.

In testimony whereof I affix my signature. 90
